UNITED STATES PATENT OFFICE.

MONTFORD MORRISON, OF NEW YORK, N. Y.

X-RAY TUBE.

Application filed June 16, 1921. Serial No. 477,898.

This invention relates to improvements in electron tubes and more especially to such tubes operated for the purpose of producing Roentgen or X-rays.

5 An object of the invention is the provision of an electron tube in which electrons are produced independent of thermionic emission.

Another object of the invention is the provision of a cathode, composite in nature, and circuit arrangement therefor, whereby electrons are withdrawn from a cold portion of the cathode.

Another object is the provision of an electron tube free from luminous bodies.

A further object of the present invention is the provision of an electron tube having a commercially long life.

A still further object of my invention is the provision of an X-ray device in which the source of the X-rays need not be electrically connected to a high voltage circuit.

Other objects will be apparent from the following specification.

25 In the present state of the art of generating Roentgen or X-rays, it is necessary to cause electrons to bombard a target at a velocity sufficiently high to cause X-rays to emanate therefrom. The necessary electrons 30 have been derived in prior devices either from a small quantity of ionizable gas contained in the tube or from an element operated to emit electrons thermally.

X-ray tubes containing gas are inferior 35 to high vacuum tubes for certain classes of X-ray work; they generate, for example, softer rays, that is to say, rays of lower penetrability than those generated by high vacuum tubes.

40 Tubes which derive the necessary electrons from a thermally electron-emitting cathode have a limited life because of the very high temperature at which the cathode must be maintained.

45 My present invention differs radically from tubes of the prior art, although it may be a high-vacuum device, which might, of course, contain a slight amount of residual gas. I have found that it is not necessary to

50 employ an incandescent body as a source of electrons for the generation of X-rays and that they may be withdrawn from a cathode operating at room temperature or a temperature below incandescence if a sufficiently

55 high potential gradient exists in the tube.

The ordinary construction of X-ray tubes

can not be used in applying the principle of my invention inasmuch as the necessary potential gradient can not be generated in such tubes. However, by means of a special construction I am enabled to secure a sufficiently high potential gradient and a field sufficiently intense to withdraw electrons from a comparatively cold cathode when employing voltages of a practicable value.

It is obvious that the maintenance of the cathode at a non-luminous temperature gives to it and therefore to the tube as a whole, an indefinitely long life, whereas a cathode operating at incandescence is naturally limited in life due to evaporation.

In addition to utilizing, for the generation of X-rays, the primary electrons which are extracted from a cold cathode my device makes use of secondary electrons which are generated by the impact of a portion of the primary electrons on a solid metallic element. It is known that for every electron which collides with a metal, a large number of secondary electrons are emitted therefrom. The utilization of this phenomenon is an advantage in that a second source of electrons is provided.

As another novel and useful feature, my invention makes possible a tube in which the body acting as the source of X-rays need not be connected to a source of high-potential as in tubes of the prior art, although it may be so connected if desired. The advantage of having the source of X-rays free from high potential lies in the fact that an intense electrostatic field, with the consequent liability to puncture the envelope, is thereby avoided.

An embodiment of my invention comprises a cathode of any desired form operating at a temperature below which electrons may be thermally emitted therefrom, high potential means for withdrawing primary electrons from the comparatively cold cathode and adapted to emit secondary electrons when the primary electrons impinge thereon and a body disposed in the path of the electron stream adapted to emanate X-rays when electrons impinge thereon.

My invention will be best understood by reference to the following description taken in connection with the accompanying drawings in which,

Figure 1 is an elevational view, partly in section, of one form of my improved tube; and

Figure 2 is a view of a modified form of the high potential element relatively positioned with respect to the anti-cathode.

Referring to Figure 1, showing one embodiment of my invention, an envelope is indicated at 3 consisting of any suitable material such as glass. Into the tubular end 4 of the envelope 3 is sealed a target 5 which functions as the source of X-rays and consists of a material of high atomic weight, such, for example, as tungsten. Although any suitable form may be given the target 5, it is here shown as a truncated cylinder beveled at 7 to eliminate the thin edge resulting from truncation. A lead wire 8 is shown in position to variably connect the target 5 electrically to a source of high potential 16. However, I may choose to leave the target 5 electrically free from such a source of potential.

Opposite the target 5 is a dished metallic plate 9, constituting the cathode of the tube, adapted to be self-focusing by reason of its form and positioned to present its concave surface to the target 5. The cathode 9 is provided with an electrically conducting lead wire 10 which is sealed into the tubular end 12 of envelope 3 by means of stem 14 and is electrically connected to a source of high potential 16 by means of a lead wire 18. In the operation of my device I may choose to heat this cathode to a temperature below which electrons may be emitted thermally therefrom.

Interposed between cathode 9 and target 5 in very close proximity to the cathode 9 is a conducting element 20 supported in any practical manner, and sealed into the envelope 3. The element 20 is variably connected by means of a conductor 24, sealed through the envelope at 22, to a source of high potential 16 and is preferably of a metallic nature consisting for example of a material such as aluminum. The structure of the element 20 preferably takes the form of a pointed needle, sharp edge or element of very small radius of curvature, or plurality of the same in order to secure an electric field sufficiently intense to enable electrons to be withdrawn from cathode 9.

When a high potential is impressed between cathode 9 and element 20 the former being negatively and the latter positively charged, electrons are withdrawn from the comparatively cold cathode 9. To permit the free passage of a portion of these electrons the element 20 is preferably provided with perforations or apertures like a grid and the electrons passing through these perforations are focused to impinge on the focal spot 25 of target 5 whereupon X-rays emanate from the latter body.

A fraction of that portion of primary electrons which collide with element 20 have sufficient velocity to cause secondary elec-

trons to be emitted from the latter element. Part of these secondary electrons are focused to impinge on the target and cause the emanation of X-rays therefrom.

Another combination of electrodes is shown in Figure 2, in which 5 represents an anode or target placed in close proximity to a cathode 20, which is preferably composed of refractory material and has its inner end as a sharp edge, point, or more generally has a small radius of curvature. In this instance the electrodes 5 and 20 are to be connected as usual to a source of high potential and are of course enclosed within an evacuated envelope. In accordance with Fig. 2, the electrode 20 constitutes the cathode from which electrons may be withdrawn to impinge on the anode 5, at high velocity, to generate X-rays.

In radiographic work it is obviously necessary to exclude light from the plate on which the image falls. In employing tubes of the prior art which required an incandescent element as a source of electrons it was necessary to provide means to prevent light from such source from falling on the image plate. My tube avoids this difficulty by not having any luminous elements therein.

While the preferred embodiment of the invention has been illustrated, it will be understood that many structural changes may be effected therein and it is, therefore, desired to be understood that the invention is to be limited only by the scope of the appended claims.

What is claimed is:

1. In an X-ray device of the high-vacuum type, in which electrons are given the necessary velocity by a source of high potential, a target positioned to receive at least a portion of said electrons, said target being electrically free from a high-potential source.

2. In a high-vacuum electron tube, a cathode and perforated means at high potential, in close proximity thereto, whereby it is adapted to have electrons withdrawn therefrom.

3. In an X-ray device, the combination of a cathode operating at a temperature below that which electrons may be emitted thermally therefrom and a perforated element at high potential comprising portions of a very small radii of curvature in close proximity thereto, for withdrawing electrons therefrom.

4. In an X-ray device, perforated high-potential means closely positioned with respect to and adapted to withdraw electrons from a cathode operating at a temperature below which electrons may be emitted thermally therefrom.

5. In an X-ray device, a self-focusing cathode and perforated means comprising sharp portions for drawing electrons there-

from by establishing a high-potential gradient therebetween, and a target separate from said means.

6. In an X-ray device, a target, a cathode and a high potential element separate from said target and positioned in close proximity to the cathode and comprising a pointed electrode.

7. In an X-ray device, a target, a cold cathode, emitting primary electrons and means separate from said target and interposed in the path of the electrons adapted to allow the free passage of a portion of said electrons, said means being adapted to constitute a source of secondary electrons when the primary electrons impinge thereon.

8. In an X-ray device having a target and a cooperating cathode operable at a temperature below which electrons may be emitted thermally therefrom, perforated means interposed between said target and said cathode in close proximity to said cathode for withdrawing electrons therefrom.

9. In an X-ray device, the combination of a target, a source of electrons operating at a temperature below which electrons may be emitted thermally therefrom and perforated means at high potential for extracting electrons from said source.

10. In an X-ray device, the combination of a target, a source of electrons operating at a temperature below which electrons may be emitted thermally therefrom and a sharp high-potential element in close proximity thereto.

11. In an X-ray device, the combination of a cathode electrically connected to a source of high potential, a source of X-rays electrically free from the source of high potential and a high-potential element disposed in close proximity to said cathode.

12. In an X-ray device, the combination of a target, a cathode operating at a temperature below which electrons may be emitted thermally therefrom and a high potential pointed grid through which primary electrons are emitted by said cathode to said target.

13. In an X-ray device, the combination of a target, a cathode operating at a temperature below which electrons may be emitted thermally therefrom and a high potential element operating to extract electrons from said cathode, closely positioned thereto and disposed in the path of a portion of the electrons emitted from said cathode

whereby said element becomes the source of secondary electrons when primary electrons collide therewith.

14. In an X-ray device, the combination of a target, a cathode emitting primary electrons at a temperature below which they may be thermally emitted therefrom and a closely spaced element at high potential and emitting secondary electrons at a temperature below which electrons may be thermally emitted therefrom.

15. The combination with a source of high potential, of an X-ray device comprising a sealed envelope, a target, a cold cathode and an intermediate element electrically connected to the source of high potential and disposed in close proximity to said cathode for withdrawing electrons therefrom.

16. An X-ray device comprising a sealed envelope, an anode, a cooperating cathode, said cathode operable at a temperature below which electrons may be emitted thermally therefrom and means at high potential for extracting electrons from said cathode.

17. An X-ray device comprising an evacuated sealed envelope, a target therein adapted to emanate X-rays, a cooperating cathode operating at a temperature below which electrons may be emitted thermally therefrom and means connected to a source of high potential interposed between said anode and said cathode in close proximity to said cathode for extracting the electrons therefrom.

18. The method of generating X-rays comprising withdrawing electrons from a body at a temperature below that at which electrons may be emitted thermally therefrom by establishing a high-potential gradient near a source of electrons, to cause electrons to impinge on another body spaced farther off.

19. The method of generating X-rays which consists in connecting to a source of high potential an electrode which functions at a temperature below which electrons may be emitted thermally therefrom, withdrawing electrons from said electrode by means of a high-potential element comprising sharp portions disposed in close proximity thereto and causing said electrons to impinge on a source of X-rays.

In testimony whereof, I have hereunto subscribed my name this fifteenth day of June 1921.

MONTFORD MORRISON.
